UNITED STATES PATENT OFFICE

FRANK M. SCHWARTZ, OF NEW YORK, N. Y.

DOLL

Application filed December 12, 1931. Serial No. 580,513.

This invention relates to new and useful improvements in a doll and process for manufacturing the same.

The invention has for an object the construction of a doll which is characterized by the provision of rubberized or gummed ravel-proof fabric appliqued thereon to form the features thereof and supplementarily secured with stitches.

10 As a further object of this invention it is proposed to construct the doll from a variety of colored fabrics pieced together so that it resembles a dressed doll, and to stuff this material in the formation of the doll proper.

15 Furthermore, as another object of this invention it is proposed to form the features of the doll by placing preshaped and cut gummed ravel proof applique material or patches upon the material of the doll and 20 moving the cut applique pieces with one's finger along to positions which produce satisfactory expressions either by skill or by following preprinted outlines on the face or other part of the doll, and thereafter stitching 25 the applique in place.

Furthermore, the invention also proposes superimposed applique arranged on an already appliqued surface so that the upper ones may be rearranged or removed to change 30 the expression of the doll.

Another object of this invention is the construction of an article of the class described which is of simple, durable construction, dependable in use and efficient in operation, 35 which can be manufactured and sold at reasonable cost.

For further comprehension of the invention, and of the objects and advantages thereof, reference will be had to the following 40 description and accompanying drawing, and to the appended claims in which the various novel features of the invention are more particularly set forth.

In the accompanying drawing forming a 45 material part of this disclosure:—

Fig. 1 is an elevational view of a doll constructed according to this invention.

Fig. 2 is a side elevational view thereof.

Fig. 3 is a sectional view taken on the line 50 3—3 of Fig. 1.

Fig. 4 is a fragmentary view of a portion of Fig. 1 showing in detail the applique which forms the expression of the face.

Fig. 5 is a sectional view taken on the line 55 5—5 of Fig. 4.

Fig. 6 is a view similar to Fig. 4 but illustrating a modification.

Fig. 7 is a sectional view taken on the line 7—7 of Fig. 6.

The doll, according to this invention, comprises material in the form of a doll and having preformed and cut ravelproof applique pieces or patches 10 gummed on one side and pasted thereon for forming the features thereof. This pasted applique is permanently secured down by stitches 11 along the perimeters thereof. The material forming the doll is such as to simulate a completely dressed doll. The formed material is directly stuffed with kapok, sawdust or other similar stuffing material 12. The doll is shown to have a head 13 provided with a hat 14 and having a band 15 at the front. Hair 16 extends from beneath the hat. A collar 17 connects the head to the body portion 18 which is decorated to simulate a jersey. Hands 19 are shown projecting from the sleeves of the jersey. The jersey ends in a band 20 below which the legs 21 project. These legs have pieces 22 secured upon the bottom ends to simulate 70 shoes. 75 80

The preformed applique is ravelproofed to improve the appearance of the doll by forming finished unravel edges and is made sanitary for a child to handle since the edges do not contain removable threads. 85

The applique or patches 10 are formed with ravelproof material gummed at 23, on the rear sides. This gummed applique should be pressed with one's finger in its proper place against the material of the doll and shifted about until it assumes a position in which the expression of the doll is what is desired. The gum is supplemented with 90 stitches 11. The heat and pressure of one's finger is applied to secure the applique in position but still allow the applique to be shifted on the material of the doll by lifting or raising the applique material and thereafter replacing it in the desired place 95 100

without leaving any strain on the material it was previously pressed against.

In the modified form illustrated in Figs. 6 and 7, another applique 24 with gummed material 25 on its rear face is shown superimposed upon the applique 10. The applique 24 is of a larger size so as to completely cover the lower applique or the lower applique may be only partially covered by the super-imposed applique. It is arranged in place by the pressure and heat of the finger on the gummed side, lifting it to be shifted around to the best position, and then securing it permanently with the addition of stitches 26. The expression of the doll may be changed by cutting the stitches 26 and removing the top applique 24 so that the bottom applique is now exposed.

It is to be understood that the shape, features and action of the doll may be changed as desired and that any number of appliques or patches may be secured on any part of the doll.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new, and desire to secure by United States Letters Patent is:—

35 1. A doll, comprising material in the form of a doll, applique patches thereon to form the features thereof, larger applique patches over said patches to form different features

thereof, and means to hold the outer applique patches in place to allow removing to expose the inner ones.

2. In a doll having features, means for changing the features, comprising applique patches in the form of different features attached upon the doll so as to cover the original features. 70

3. In a doll having features, means for changing the features, comprising applique patches in the form of features, and means for attaching said patches upon the doll so as to cover the original features, said latter means destructable to cause the patches to be removable to expose the original features. 75 80

4. A doll, comprising a cloth casing and stuffing material in the form of a doll, applique patches thereon to form the features thereof, large applique patches over said patches to cover the features thereof, said latter mentioned applique patches being stitched to the cloth casing material in a manner so as to be removable to expose the other applique patches. 85

5. A doll, comprising a cloth casing and stuffing material in the form of a doll, applique patches thereon to form the features thereof, large applique patches over said patches to cover the features thereof, said latter mentioned applique patches being stitched to the cloth casing material in a manner so as to be removable to expose the other applique patches, the stitches of said larger applique patches being arranged around the perimeter of said patches. 95 100

In testimony whereof I have affixed my signature.

FRANK M. SCHWARTZ.
